(57) **CLAIM**

The ornamental design for a window and door molding, as shown and described.

DESCRIPTION

FIG. 1 is a front perspective view of a window and door molding showing our new design;

FIG. 2 is a rear perspective view of the molding shown in FIG. 1;

FIG. 3 is a front elevation view of the molding shown in FIG. 1;

FIG. 4 is a rear elevation view of the molding shown in FIG. 1;

FIG. 5 is a left-side elevation view of the molding shown in FIG. 1;

FIG. 6 is a right-side elevation view of the molding shown in FIG. 1;

FIG. 7 is a top plan view of the molding shown in FIG. 1;

FIG. 8 is a bottom plan view of the molding shown in FIG. 1; and,

FIG. 9 is a front perspective view, exploded, of the molding shown in FIG. 1.

The window and door molding is shown with a symbolic break line in its length. The appearance of any portion of the article between the break lines form no part of the claimed design.

1 Claim, 9 Drawing Sheets(56)
